COATING APPARATUS

Alfred L. Kronquest, Syracuse, N. Y., assignor to
 Continental Can Company, Inc., New York,
 N. Y., a corporation of New York

Application October 11, 1943, Serial No. 505,759½

9 Claims. (Cl. 91—44)

This invention relates to coating apparatus and more particularly to apparatus for coating the interiors of containers with flowable material by flooding the containers with such material and then permitting the surplus material to drain off, leaving an adherent coating on the container interior wall surfaces.

Apparatus embodying the invention is adapted for use in coating articles, for example the interiors of containers, with various flowable substances such as cold water and glue mixtures, and thermoplastic material.

An object of the invention is to provide improved apparatus of this kind which is of simple construction and is efficient and rapid in operation.

Another object of the invention is to provide apparatus of the character stated in which delivery of flowable material from a source of such material maintained under pressure to a device for delivering the material to an article to be coated is controlled by a valve which is by-passed by a restricted passage affording constant communication between the material source and the delivery device, the arrangement being such that there will be a constant but restricted flow of material through the delivery device even when the valve is closed, so as to prevent setting or congealing of the material in the delivery device.

Another object of the invention is to provide apparatus of this kind which is simple but reliable in operation and in which the danger of congealing of the coating material in passages through which the material flows is minimized.

Another object of the invention is to provide apparatus of the character referred to in which a pump for placing the thermoplastic material under pressure, the pump intake and discharge passages, a pressure chamber which receives the material discharged by the pump, and a valve for controlling the delivery of the coating material are all immersed in and therefore heated by a supply of thermoplastic material constantly maintained at a temperature high enough to render the material plastic and flowable.

Another object of the invention is to provide apparatus of this kind in which a delivery tube or the like extends outwardly beyond the supply of heated thermoplastic material and in which means are provided for enabling a restricted flow of thermoplastic material from the pressure chamber out through the delivery tube, even when the valve is closed, so that the material will not remain stationary in the tube and therefore will not be permitted to congeal in the tube.

Another object of the invention is to provide apparatus especially suited for coating the interiors of containers with thermoplastic material which is flowable at elevated temperatures but which congeals at ordinary or "room" temperature.

Other objects will become apparent from a reading of the following detailed description, the appended claims and the accompanying drawings.

10 In the drawings:

Figure 1 is a front elevation of apparatus embodying the invention, with parts broken away and others shown in section.

15 Figure 2 is a top plan view of the apparatus shown in Figure 1.

Figure 3 is a vertical section on the line 3—3 of Figure 1 drawn on an enlarged scale.

20 Figure 4 is a fragmentary vertical sectional view of a container support, coating valve mechanism, and associated frame structure drawn on an enlarged scale.

Figure 5 is a plan view of an adapter ring.

In the embodiment of the invention shown in the accompanying drawings, a frame A serves 25 to support a supply tank B adapted to contain the thermoplastic coating material F, and a heating jacket C embracing a substantial portion of the tank B and being adapted to contain a quantity of heat transferring fluid 14 in contact with the walls of the tank B. Coating units D carried by the frame structure are mounted in alignment at the top of the apparatus and are adapted individually to receive inverted containers X—Y which are to be coated or treated. A pump generally designated E is immersed in the coating or treating fluid F in the tank B and is arranged to be driven continuously by a motor G. The pump E delivers heated coating material to the units D which support the containers to be treated, but normally the coating material is held back by valve mechanism to be described later. In order to deliver the coating material to the inside of a container, the container is simply pushed downwardly so as to open the associated valve and cause the interior of the container to be flooded with the coating material F.

Referring in more detail to the illustrative 30 form of construction, equipment for maintaining the coating fluid hot and thus plastic and flowable includes a gas pipe 1 extending underneath the jacket C and having a vertical extension 2 secured to one end of the jacket C by a clamp 3. Branch pipes 4 extending horizontally from

the pipe 4 at spaced intervals are provided with vertical extensions 5 which lead respectively to manually operable valves 6 controlling the flow of gas to a plurality of burner units 7. The burner units may be of any suitable construction, those shown including mixing valves 8 and burner heads 9. The burner heads preferably are provided with supporting arms 10 suspended from an angle rail 11 carried by a plurality of brackets 12 secured as at 13 to the jacket tank C for vertical adjustment.

The jacket tank C is substantially filled with a suitable heat transferring fluid 14, such as oil. In order to maintain the jacketing fluid at the desired temperature, a thermostatically controlled gas valve unit 15 having a heat responsive element 16 immersed in the fluid 14 is interposed between the gas pipe line 1-2 and a fitting 17 which is adapted to be connected to a source of gas supply. Although the flames at the burner heads 9 can be adjusted individually by the valves 6 when the apparatus is set up and operation is started, the thermostatic valve 15 will respond to slight changes in temperature of the heating fluid 14 for controlling the supply of gas to all of the burners simultaneously and for thus maintaining the heat transferring fluid at a substantially constant temperature.

The pump E may be of any standard or suitable construction and is immersed in the coating material F with its intake passage 18 arranged to receive fluid directly from the tank B. The pump discharge passage 19 is arranged to deliver coating fluid under pressure into a pressure manifold or chamber 20 supported within the tank B, the fluid under pressure within the chamber 20 being delivered into the containers under the control of the operator in a manner to be described later.

The pump E includes a shaft 21 coupled as at 22 to a shaft 23 journaled in a bearing 24 and equipped at its upper end with a bevel gear 25. The gear 25 meshes with a bevel pinion 26 secured to one end of a shaft 27 journaled in bearings 28 and equipped at its outer end with a pulley 29. A belt 30 is trained around the pulley 29 and a pulley 31 on the motor G. The motor may be mounted for adjustment to vary the tension of the belt 30, and in the form shown the motor is carried by a bracket 32 pivoted as at 33 on the frame A. The bracket may be swung to adjusted position by a screw and traveling nut adjusting device indicated at 34.

As shown in Figure 3, a member supported on the tank B is formed with a housing 35 for the gears 25 and 26 and with a funnel shaped filler opening 36 adapted to be closed by a lid 37. A drain pipe 36a communicates with the bottom of the tank B and is controlled by a valve 36b.

As previously stated, coating fluid is delivered into the containers only when the latter are depressed by the operator. Inasmuch as the pump constantly delivers fluid under pressure to the manifold 20, it is desirable to provide a by-pass connection between the manifold and the tank B. Such a connection is indicated at 38 as comprising a conventional pressure relief or bypass device which preferably is adjustable to maintain a desired pressure within the manifold or chamber 20.

The coating units D may all be of the same construction. Each unit D includes a valve generally designated 39 and comprising a fixed casing 40 having threaded connection at 41 with the top of the manifold 20. The casing 40 is

formed with a valve seat 42 adapted to be engaged by a valve disc 43 formed on a valve piston 44 mounted for vertical reciprocation in a bore 45 formed in the casing 40. A spring 46 interposed between each valve disc 43 and a ring 47 screwed as at 48 into the bottom of the valve casing 40 yieldably urges the valve piston 44 upwardly, and yieldably holds the valve disc 43 on its cooperating seat 42. The ring 47 is formed with a plurality of openings 49 which afford communication of the manifold 20 with a chamber 50 inside of the valve casing 40.

The valve piston 44 is formed with a circumferential recess 51 communicating through radial openings 52 with a bore 53 in the piston 44. A counter-bore 54 in the piston 44 is threaded to receive the lower end of a vertically extending delivery tube 55.

The valve piston 44 furthermore serves as a seat for a container support 56 having a vertically bored hub 57 adapted to fit over the associated delivery tube 55. The container support 56 includes a bottom 58 formed with drain openings 59 and provided with vertical webs 60 which extend from the hub 57 to a vertical flange 61.

Figure 4 shows the parts of one container coating unit D in normal positions with a container X resting on the support 56 in readiness for being coated with the fluid F. In order to cause delivery of the fluid to coat the inside of the container, the operator presses downwardly on the container X which forces the support 56 downwardly and moves the valve piston 44 to disengage the valve disc 43 from the seat 42. With the valve thus opened the heated treating fluid F flows upwardly through the openings 49 into the chamber 50 and thence through the openings 52, the bore 53, and into the tube 55. The upper end of the tube is open and the fluid is driven under pressure out of the tube so as to flood the interior of the container X, thus assuring contact of the fluid with all portions of the container inner surface. The fluid will be circulated through the container during the flooding operation and will pass out through the openings 59 in the support 56 and thus be returned to the tank B.

In the practical use of the apparatus, containers to be coated are placed on each of the units D and only one container and associated support 56 are pressed downwardly at a time. The operator may start at either end and press the aligned containers downwardly in succession, allowing each depressed container to move back to normal position before the next container is depressed. In this way while a container is being held depressed, other and previously flooded containers will be standing in raised position and may be left there long enough to permit the excess coating fluid to drain completely from the supporting member 56 back into the tank B.

Inasmuch as the valves 39 of the units D remain closed during substantial periods when containers are draining, there is a tendency for the coating material to congeal within relatively cool delivery tubes 55. In order to prevent stoppage of the tubes 55 due to congealing of the coating material, each valve piston 44 is formed with a small opening 62 which communicates with the bore 53 directly under the tube 55. It will be apparent that when the valve 39 is held closed following the delivery of fluid through the tube 55, heated thermoplastic material will flow slowly up through the opening 62, the bore 53, and the tube 55, thereby maintaining the treating fluid in motion within the tube 55 and preventing the ma-

terial from cooling enough to cause it to congeal. The opening 62 is of such small flow capacity that the material passed therethrough will flow slowly down the outside of the tube 55 and out through the drain openings 59 without being ejected substantially above the top of the tube 55 and without coming in contact with the container X.

The pump E, the pump intake and discharge passages 18 and 19, the pressure chamber 20 and the valves 39 are all below the level of the heated thermoplastic material in the supply tank B, and consequently there can be no congealing of the material in these parts. Congealing of material inside the tubes 55 when their associated valves 39 remain closed is prevented by the constant flow of heated thermoplastic material through the by-pass passages 62 and the tubes 55.

Preferably the tank B is provided with a cover 63 formed with circular upstanding skirts 64 respectively above and concentric with the supports 56 of the units D.

The container supports 56 are loosely mounted on the valve pistons 44 and therefore may easily be adjusted so as to be adapted to receive containers of different sizes. In Figure 1 the supports 56 of the four units D nearest the right hand end of the drawings are adapted to receive containers X of a relatively large size, whereas the two other supports are shown as being adapted for receiving containers Y of relatively small size. The supports 56 of the two left hand units D are raised slightly by means of adapter or spacer bushings 65 to compensate for the lesser height of the containers Y. Adapter rings 66 formed with centering flanges 67 are inserted inside the flanges 61. It will be apparent that by using adapter bushings 65 and adapter rings 66 of different sizes, any size container within reasonable limits may be supported in the proper position relative to the delivery tubes 55.

Although the embodiment of the invention disclosed herein has features of construction rendering it especially suitable for coating articles with thermoplastic material, it will be apparent that apparatus constructed in accordance with the invention may be used for coating articles with other flowable substances, e. g., cold water and glue mixtures, as previously mentioned.

The apparatus disclosed herein embodies the invention in the form now preferred, but it will be understood that changes may be made without departing from the invention as defined in the claims.

I claim:

1. In apparatus of the character described, means for delivering flowable material to an article to be contacted by said material; means for maintaining the flowable material under pressure necessary to effect delivery of the material; a valve interposed between said two means for controlling the delivery of said material; and a restricted by-pass passage for affording communication between said two means independently of the condition of said valve, said by-pass passage opening into the means in which the flowable material is maintained under pressure at a level at least as low as the level of the material therein.

2. In apparatus for coating the interiors of containers with flowable material, a chamber for maintaining a supply of the flowable material under pressure; a delivery tube extending upwardly and being adapted to project into an inverted container; a valve interposed between

5 said chamber and said delivery tube for controlling the delivery of said material and when open having a flow capacity sufficient to pass said material rapidly enough to flood the container; and a by-pass passage for affording constant communication between said chamber and said delivery tube irrespective of the condition of said valve, said by-pass passage having sufficient flow capacity to enable the flowable material 10 constantly to flow upwardly through said tube, out of the top of the tube, and thence downwardly outside of the tube without being ejected substantially above the top of the tube.

3. In apparatus for coating the interiors of containers with thermoplastic material, a chamber for maintaining a supply of the thermoplastic material under pressure; a delivery tube extending upwardly and being adapted to project into an inverted container; a valve interposed between said chamber and said delivery tube for controlling the delivery of said thermoplastic material and when open having a flow capacity sufficient to pass said material rapidly enough to flood the container; means for heating the thermoplastic material in said chamber and in contact with said valve to such a temperature that the heated material will not congeal in said chamber or in said valve; and means for preventing congealing of the thermoplastic material in said delivery tube when said valve is closed comprising a by-pass passage for affording constant communication between said chamber and said delivery tube irrespective of the condition of said valve, said by-pass passage having sufficient flow capacity to enable the thermoplastic material constantly to flow upwardly through said tube, out of the top of the tube, and thence downwardly outside of the tube without being ejected substantially above the top of the tube.

4. In apparatus for coating the interiors of containers with flowable material, a chamber for maintaining a supply of the flowable material under pressure; a delivery tube extending upwardly and being adapted to project into an inverted container; a valve interposed between said chamber and said delivery tube for controlling the delivery of said material and when open having a flow capacity sufficient to pass said material rapidly enough to flood the container; a container support mounted on said delivery tube and being connected to said valve for opening the latter when the support is moved downwardly, said support being adapted to receive the open end of an inverted container whereby depressing of the container will move the support downwardly and said support being constructed to enable drainage of material from the flooded container; and a by-pass passage for affording constant communication between said chamber and said delivery tube irrespective of the condition of said valve, said by-pass passage having sufficient flow capacity to enable the flowable material constantly to flow upwardly through said tube, out of the top of the tube, and thence downwardly outside of the tube without being ejected substantially above the top of the tube.

5. In apparatus for coating objects with thermoplastic material, a supply tank for the thermoplastic material; a pump mounted in said tank below the level of thermoplastic material therein; a pressure chamber in said tank below the thermoplastic material level, said pump having an intake passage located in said tank below the thermoplastic material level for receiving

thermoplastic material from said tank and a discharge passage communicating with said pressure chamber and being located in said tank below the thermoplastic material level; a tube for delivering thermoplastic material from said pressure chamber for application to an article to be coated, the delivery end portion of said tube extending beyond said supply tank; a valve mounted in said tank below the thermoplastic material level for controlling the flow of thermoplastic material from said pressure chamber out through said delivery means; means for maintaining said thermoplastic material hot enough to be flowable under pressure; and a restricted by-pass passage for affording constant communication between said pressure chamber and said delivery tube independently of the condition of said valve.

6. In apparatus for coating the interiors of containers with thermoplastic material, a chamber for containing thermoplastic material under pressure; a plurality of spaced delivery units, each of said units comprising an upwardly extending delivery tube, a normally closed valve interposed between said tube and said pressure chamber, means for supporting a container in inverted position over said tube and being constructed to permit drainage of material from within the supported container, and means for opening the valve to effect flooding of the container; and means for maintaining said pressure chamber, said valve, and the thermoplastic material in said pressure chamber at plasticizing temperature, each of said units being provided with a restricted by-pass passage affording constant communication between said pressure tank and said delivery tube, whereby when the valve of any of said units is closed following flooding of the associated container heated thermoplastic material will flow continuously and slowly through said delivery tube without being ejected substantially above the top end of said tube.

7. In apparatus of the character described, a pressure chamber; a delivery tube; a valve interposed between said pressure chamber and said delivery tube; a member engageable by the open end of a container extending over and surround-

ing the delivery end portion of said tube; a flange on said member adapted to embrace the side walls of a container of one size engaging said member; and a removable adapter ring adapted to be fitted within and centered by said flange and having a concentric flange of smaller diameter for embracing the side walls of a smaller size container.

8. In apparatus of the character described, a pressure chamber; a delivery tube; a valve for controlling communication between said chamber and said tube and comprising a casing mounted on said chamber and a reciprocable valve element in said casing, said tube being connected to said reciprocable element for movement therewith; a member mounted on said tube for adjustment longitudinally thereof and being engageable by the open end portion of a container extending over and surrounding the delivery end portion of said tube for maintaining the container with its closed end spaced from the delivery end of said tube, said member being adapted normally to bear against said valve element; and means for maintaining said member in adjusted position longitudinally of said tube and spaced from said valve element.

9. In apparatus of the character described, a pressure chamber; a delivery tube; a valve for controlling communication between said chamber and said tube and comprising a casing mounted on said chamber and a reciprocable valve element in said casing, said tube being connected to said reciprocable element for movement therewith; a member mounted on said tube for adjustment longitudinally thereof and being engageable by the open end portion of a container extending over and surrounding the delivery end portion of said tube for maintaining the container with its closed end spaced from the delivery end of said tube, said member being adapted normally to bear against said valve element; and a spacer bushing adapted to be interposed between said member and said valve element for maintaining said member relatively closer to the delivery end of said tube than when said member engages said valve element.

ALFRED L. KRONQUEST.
